UNITED STATES PATENT OFFICE.

GEORGE H. RICKE, OF CINCINNATI, OHIO, ASSIGNOR TO WILLIAM T. HILL,
OF CINCINNATI, OHIO.

FRUIT-JAR.

SPECIFICATION forming part of Letters Patent No. 723,406, dated March 24, 1903.

Application filed October 18, 1901. Serial No. 79,090. (No model.)

To all whom it may concern:

Be it known that I, GEORGE H. RICKE, a citizen of the United States, residing at the city of Cincinnati, in the county of Hamilton and State of Ohio, have invented new and useful Improvements in Fruit-Jars, of which the following is a specification.

The object of my invention is to produce a cheap, simple, and efficient fruit-jar, relating more especially to glass jars. In the glass jars now in use metal caps and gaskets are used to seal the mouth of the jar. The gaskets, usually made of rubber, wear out quickly. They rot easily and tear and slip when the screw-cap is screwed down in place, allowing air to enter, the fruit to be preserved molding and spoiling at the top and often the contents of the entire jar being rendered unpalatable and worthless. It is almost impossible to prevent a mold from settling at the top of the preserved fruit when the present jars are used. The fruit is also rendered unpalatable by coming in contact with the metal caps. My invention obviates all these objections and a hermetically-sealed jar is the result, preserving the fruit properly and preventing it from becoming moldy, unpalatable, and unwholesome.

In the accompanying drawings, forming part of this specification, Figure 1 is a side view of my improved fruit-jar looking at it from that side which shows the locking-wire from the end. Fig. 2 is a side view of my improved fruit-jar looking at it from that side which shows the locking-wire from the side. Fig. 3 is a side view of the jar, parts being broken away at the top to show the manner in which the lid, top, or cap fits in the mouth of the jar, the parts being shown in section. Fig. 4 is a top view of my improved fruit-jar.

A represents the jar; B, the top, cap, or lid; C, the locking-wire, and D the binding wire or string.

The fruit-jar is preferably made of the shape shown in the drawings—that is, cylindrical shape—interrupted near the top by the encircling depression or neck E, in which the binder D fits.

The mouth of the jar A is preferably of shape shown, having annular top, rim, or

edge a and an annular seat a', on which the lid or cap B rests. The rim a is also notched at b, as shown, so that the locking-wire C can rest therein.

The cap or lid B is usually made of the shape or contour shown, being oval on top and at the center being crossed by a recess G, into which the locking-wire C fits and rests, and on the under side the lid B is provided, a short distance from its edge, with an annular flange F.

The lid B rests on the seat a', a slight space being left between the edge of the lid and the mouth of the jar for the sealing fluid P, the flange F fitting into the jar just at the edge of the seat a'. This construction binds the paper gasket b' tightly on the edge between the lid and jar and keeps any sealing fluid from entering the jar.

The locking-wire has the depending arms H, which arms are turned up at their ends to receive the binder D, so that the locking-wire C can be properly and rigidly held in position in the recess F and in notches b in the top edge a of the jar A. The locking-wire C, resting in the recess F and notches b, keeps the lid from turning.

The top of the lid or cap B is preferably flush with the top of the jar or rests slightly below it, so that one jar can be set on the other in shipping it for convenience.

The jar is used as follows: The fruit to be preserved is poured into the jar A, and after it has cooled sufficiently the lid or top B is placed on the seat a', resting on the gasket b'. The locking-wire C is then put in place and held down and in place by the binder D. The paraffin or other sealing fluid or wax P is then poured into the space d between the lid and the jar's mouth, and the jar is hermetically sealed.

If desired, the binder could be dispensed with and the locking-wire so formed as to rigidly hold the cap in place. Instead of a wire a locking-plate might be used.

I may alter the shape of the mouth of the jar and dispense with the flange F on the lid, and I may dispense with the use of the paper gasket.

Instead of a glass lid I may make a paper lid stamped into shape or may make it of

some other preferable material. The jar of course is preferably made of glass, but may be made of other material.

It will be readily seen that this jar can be 5 made cheap, that it can be easily handled, that it can be packed and shipped at a minimum cost, that it is simple, and that it will preserve the fruit properly, excluding the air and preventing the fruit from becoming moldy 10 and unpalatable.

What I claim as new and of my invention, and desire to secure by Letters Patent, is—

1. In a fruit-jar, a jar-body having a seat at its mouth in combination with a lid, said 15 lid resting on said seat, the lid lying wholly within the mouth of the jar, the lid and mouth edge of the jar carrying notches lying in the

same straight line, in combination with a locking-wire which fits said notches, substantially as and for the purposes specified. 20

2. In a fruit-jar having at its mouth a seat a', in combination with flanged lid B, said lid B resting on said seat a', the lid B lying wholly within the mouth of the jar, the said lid B, having notch G, cut therein, the edge 25 of the mouth of the jar having notches b, the notches G, and b lying in the same straight line, in combination with locking-wire C, fitting the said notches, and a binder D, substantially as and for the purposes set forth. 30
